US00D907904S

(12) **United States Design Patent** (10) Patent No.: **US D907,904 S**
(45) Date of Patent: **** Jan. 19, 2021**

(54) **SHOE**(71) Applicant: **adidas AG**, Herzogenaurach (DE)(72) Inventors: **Jacques Perrault**, Portland, OR (US);
Derek Andrew Luther, Portland, OR (US); **Berin Skye B**, Portland, OR (US); **Marco Florian Kormann**, Fürth (DE)(73) Assignee: **adidas AG**, Herzogenaurach (DE)(**) Term: **15 Years**(21) Appl. No.: **29/672,125**(22) Filed: **Dec. 3, 2018**

Primary Examiner — T Chase Nelson(74) *Attorney, Agent, or Firm* — Sterne, Kessler, Goldstein & Fox P.L.L.C.**CLAIM**

The ornamental design for a shoe, as shown and described.

DESCRIPTION

FIG. 1 is a left side view of a shoe showing the claimed design; and,

FIG. 2 is a top view thereof.

The dot-dash broken lines in the figures and the areas within the dot-dash broken lines show portions of the shoe that form no part of the claimed design.
